UNITED STATES PATENT OFFICE.

ISAAC F. RUBEL, OF CHICAGO, ILLINOIS.

DESIGN FOR A KNIFE-HANDLE.

SPECIFICATION forming part of Design No. 16,742, dated June 15, 1886.

Application filed March 16, 1886. Serial No. 195,473. Term of patent 3½ years.

To all whom it may concern:

Be it known that I, ISAAC F. RUBEL, a citizen of the United States, residing at Chicago, in the county of Cook and State of Illinois, have invented and produced a certain new and original Design for Knife-Handles, of which the following is a specification, reference being had to the accompanying drawing, forming a part thereof, said drawing being a side view of a knife whose handle contains my new design.

My design relates to the ornamentation of the lateral surfaces of knife-handles by certain figures on the bolster and tip.

15 In the drawing, A is the side plate of the handle. B is the bolster, and C is the tip.

The figures A' A' upon the bolster and tip constitute my design. They consist each of alternating longitudinal and transverse sections or blocks joined successively to form a continuous figure of zigzag outline. The two

figures at each end are similar but reciprocal to each other—as it were, “rights and lefts.” They each commence with a longitudinal section setting off from the body of the middle portion, A, and terminate with a transverse section, said terminal transverse sections of the two reciprocal zigzags standing in toward each other.

I claim—

30 The design for a knife-handle herein shown and described, comprising the figures A' A' on the bolster and tip in the form of reciprocal zigzags made up of alternating longitudinal and transverse sections.

35 In testimony whereof I have hereunto set my hand, in the presence of two witnesses, at Chicago, Illinois.

ISAAC F. RUBEL.
